DIEING OUT MACHINE

George F. Ryan, Peabody, Mass., assignor to
 United Shoe Machinery Corporation, Flemington, N. J., a corporation of New Jersey

Application September 1, 1944, Serial No. 552,356

16 Claims. (Cl. 164—24)

1

This invention relates to dieing out machines, and is herein illustrated in connection with mechanism for dieing out blanks, such as shoe part blanks, from sheet material by the use of cutting dies.

In cutting out shoe part blanks, it has been customary to employ cutting dies which are placed upon sheet material positioned upon a cutting block, and a presser member is used to deliver a blow to the die to produce a blank. In one type of machine which has come into extensive use and which is commonly known as a clicking machine, the blow is delivered to the die by means of an arm which is pivotally mounted at one side of the machine for movement over the block, the arm being swung out of the way after each dieing out operation and then moved back into position over the die in a new location upon the material. While machines of this type are generally satisfactory, considerable effort upon the part of the operator is required in moving the arm over the block hundreds or thousands of times each day, and considerable power is required to move the beam toward and away from the block.

In view of the foregoing, it is an object of the present invention to provide an improved dieing out machine so constructed as to minimize the effort required to operate it and which at the same time is economical in its operation. To this end and as illustrated, I have provided, in a machine of the type referred to, a die supported at the end of an arm pivotally mounted for movement across and heightwise of a cutting block, and mounted for movement transversely of the block, so that the die can readily be located in any desired position on the block, together with a hammer which is movable with the die laterally over the block in predetermined position above the die, and means for causing the hammer to deliver a blow to the die. Preferably and as shown, the die is detachably carried by a die holder, secured at the end of the arm, and there is a starting handle mounted upon the die holder for initiating power operation of the hammer. Preferably also, and as illustrated, the hammer is normally maintained in inoperative position above the die by fluid pressure means, arranged to be released upon actuation of the starting handle, there being spring means for causing the hammer to deliver a blow to the die. The construction and mounting of the arm are such that the weight of the die is carried by the arm, and the die can be readily moved into operative position on the block, thus requiring little effort upon the part of the operator. The hammer for forc-

2

ing the die through work may be of light construction and consequently the amount of power required to operate it is comparatively small.

These and other features of the invention are disclosed in the following specification and in the accompanying drawings, and are pointed out in the claims.

In the drawings,

Fig. 1 is a view in side elevation of a dieing out machine embodying one form of my invention;

Fig. 2 is an end view, partly in section, taken along line II—II of Fig. 1;

Fig. 3 is a side view, on an enlarged scale and partly in section, taken along line III—III of Fig. 2; and

Fig. 4 is a plan view of the end portion of the die holder and its supporting arm.

This machine is particularly adapted to operate upon sheet material, such as leather or fabric, to form shoe part blanks by means of cutting dies.

As illustrated in Fig. 1, the machine comprises a frame 10 carrying a cutting block 12 for supporting sheet material 14, a cutting die 16 in a holder 18 at one end of an arm 20 pivotally mounted upon a movable carriage 22 in such manner that the die can be moved over the block into any desired position on the material, and a hammer 24 also mounted upon the carriage and movable with the arm 20 into such position, that, upon actuation of a manually operable starting handle 26, the hammer delivers a blow to force the die through the material to produce a blank.

The carriage 22 upon which both the die and the hammer are supported comprises a base plate 28 mounted for movement along a rail 30, extending at right angles to one side of the block on the frame 10. The base plate is supported on rollers 32 engaging spaced upwardly disposed surfaces 34 on the rail, the plate also having rollers 36 mounted with their axes inclined to the vertical on opposite sides of the rail (see Fig. 2) and engaging beveled side surfaces 38 thereof. The plate carries a vertically extending spindle 40, upon which is mounted a casting 42 rotatable about the axis of the spindle, there being a thrust bearing 44 between the casting and the upper surface of the plate for reducing friction between the two members. Positioned upon the casting 42 is a block 46, which supports a bracket composed of two upstanding plates 48 secured in spaced relation by two laterally extending blocks 50 and 52 and bolts 53.

The arm 20 is in the form of a cylindrical rod extending between the plates 48 and pivoted

thereon by two pivot pins 54 (Fig. 2), which engage a collar 56 fixedly secured to the arm 20. The weight of the die, die holder, and associated parts is counterbalanced by a fixed counterweight 58 mounted upon an end of the arm 20.

In order to provide for the counterbalancing of dies, of different weights, which may be positioned in the holder, there is provided a movable counterweight 60 mounted on the arm 20 inwardly of the counterweight 58. The counterweight 60 is arranged for adjustment along the arm by means of a rod 62 having one end secured to the counterweight. The other end of the rod 62 is secured to a slide 64 on the arm by which the counterweight 60 can be shifted and is provided with a wing nut 66 to secure the slide in fixed position. The construction of the mountings for the carriage 22 and arm 20, just described, is such that a die 16 carried at the outer end of the arm can readily be moved into any position upon the cutting block 12 by swinging the arm about the axis of the spindle 40 and by moving the arm and the carriage along rail 30 in directions transversely of the block. Since the weight of the die is counterbalanced, the die can readily be lifted above the surface of the block by rotating the arm about its pivots 54.

The die 16 is a cutting die of the well-known mallet-handle type and has a side wall 68 terminating in a cutting edge 70, and an upwardly extending shank or handle 72. The die is arranged to be detachably secured in the holder 18 which comprises a block 74 and an upstanding spindle 76. The head is provided with a recess 78, the side walls of which have tongues 80 arranged to enter grooves 82 near the upper end of the shank 72 of the die. A spring-pressed plunger 84 in the block serves to lock the die in position in the holder. This construction facilitates the insertion in and removal from the holder of dies, of different shapes and sizes, each having a shank or handle similar to that herein illustrated.

The die holder 18 is detachably supported at the end of the arm 20 upon a bracket 86 comprising a horizontal plate 88 having therein a slot 90 (Fig. 4) terminating in a semicircular opening 92 of a diameter somewhat greater than that of the spindle 76 of the holder. The wall of the plate along the opening 92 is thickened and is adapted to engage the holder above and below a groove 94 near the upper end of the holder to locate the holder in predetermined position horizontally. A slide 96 mounted in grooves 98 in the plate 88 has a semicircular end wall 100 adapted to enter the groove 94 to lock the holder in fixed position heightwise of the plate, the slide normally being held in locking position against the spindle by a spring 102 mounted on a pin 104 secured to the slide and extending loosely through a closure plate 106. The spindle projects above the plate 88 in position to receive upon its upper end blows delivered by the hammer 24 to force the die 16 through the work.

In order to secure the bracket 86 to the arm 20, the bracket is provided with a downturned flange 108 (Figs. 1 and 4), which bears against a plate 110 on the outer end of the arm and is secured to the plate by bolts 112 extending through the flange and plate, there being springs 114 on the bolts for forcing the two parts together. The plate 110 has a tongue 116 positioned in a vertical groove 118 in the flange 108 for maintaining the bracket and arm in alinement. This construction provides a yieldable connection between the die holder 18 and its supporting arm 20, such

that the holder can rock slightly in a vertical plane so that the die 16 can move in a direction normal to the cutting block 12 during a cutting operation without likelihood of breaking the parts.

The starting handle 26 is in the form of a sleeve surrounding the spindle 76 of the die holder immediately below the plate 88, and has a key 120 positioned in a vertical keyway 122 in the spindle, thus securing the handle and spindle together for movement about the axis of the spindle in shifting the position of the die 16 angularly, while at the same time permitting movement of the handle along the spindle upwardly into engagement with the plate 88 preparatory to raising the die above the block, or downwardly to initiate a dieing-out operation, as hereinafter described. The lower end of the handle is provided with a flared skirt 124, which acts as a finger guard.

The hammer 24 is carried by a rod 126 extending between the plates 48 and pivoted thereto by means of pins 128 arranged to engage a collar 130 fixedly secured to the rod 126. The weight of the hammer is partially balanced by a counterweight 132 on the end of the rod 126. The hammer is generally cylindrical in shape, but has an attenuated striking portion 134 for engaging the upper end of the spindle 76. The pivots for the arm 20 and the rod 126 are positioned one above the other, so that the arm and rod are movable in the same vertical plane, irrespective of their angular positions about the axis of the spindle 40. The lengths of the arm and the rod and the spacing of the pivot pins 54 and 128 with relation to the height of the die 16 and die holder 18 are such that, when the die is down upon the work, the arm 20 is horizontal with the spindle 76 vertical, and when the hammer is brought down upon the spindle 76 the rod 126 will be in a horizontal position, as shown in dotted lines in Fig. 1, with the axis of the hammer vertical. This ensures that the hammer blow will be substantially normal to the cutting block which is desirable to produce perfect blanks.

In order to eliminate any likelihood of an operator getting his fingers caught between the hammer and spindle, there is provided a guard 136, preferably composed of a sheet of transparent material 138 extending along three sides of the plate 88, and projecting upwardly by a distance somewhat greater than the length of the hammer. The material 138 is supported by a metal frame comprising upper and lower U-shaped strips 140 and vertical members 142, and is secured to the plate by screws 144.

The hammer 24 is normally held in raised position, as shown in full lines in Fig. 1, by pneumatic means. To this end, the counterweight 132 on the inner end of the rod 126 is connected by a link 146, Fig. 3, to the upper end of a piston rod 148 connected to a piston 150 slidably mounted in a cylinder 152 supported on a plate 154 forming a lateral extension of the casting 42. The upper end of the cylinder is closed by a head 156 secured in position by bolts 158 extending upwardly from the plate 154. Located in the head on opposite sides of the piston rod, are two fluid passages, one of which is shown at 160, which are connected, respectively, to two fluid conduits 162 and 164 extending between the head and a cylindrical valve chamber 166 located in the block 46. A fluid supply pipe 168 is connected to the valve chamber at a point opposite the entrance of the conduit 162 to the chamber, and opposite the conduit 164 is an ex-

haust port 170 leading from the chamber to the open air. Within the chamber is a bushing 172 having near one end oppositely disposed elongated openings 174 aligned with the supply pipe 168 and with the conduit 162, and having at the other end similar openings 176 aligned with the conduit 164 and with the exhaust port 170. Within the bushing is fitted a cylindrical valve 177 having an elongated radial passage 178, for connecting the passages 174, and a similar passage 180 for connecting passages 176. The passages 178 and 180 are displaced relatively to each other through an angle of about twenty degrees, so that when one of them is positioned in alignment with passages in the bushing, the other is closed off by the wall of the bushing. Thus, with the valve and other parts in the positions shown in Figs. 2 and 3, fluid, preferably air under pressure, passes from the supply pipe 168 through passage 178 and to the conduit 162 into the upper portion of the cylinder. The passage 180 is closed, and consequently pressure in the cylinder builds up forcing the piston down, thereby raising the hammer and maintaining it in raised position. When the valve is rotated about twenty degrees into position with the passage 180 in alignment with the passages 176, the fluid supply through its valve passage 178 is shut off and the air in the cylinder is partially exhausted through the conduit 164, valve passage 180 and the port 170, thus releasing the piston and hammer.

The valve 177 is arranged to be operated to release the hammer upon depressing the starting handle 46. To this end, there is provided a pawl 182 pivoted at 184 on a bracket 186 carried by the block 46. The lower end of the pawl enters a notch 188 in a stud 190 secured to the valve. By shifting the position of the pawl, the valve can be moved to either of its extreme positions. The pawl is operated by a slide 192 having a notch 194 arranged to receive a nose portion 196 at the upper end of the pawl. The slide is arranged for reciprocation by means of a rod 198 supported by brackets 200 depending from the arm 20. The outer end of the rod 198 is connected through a series of links 202, 204, 206 supported by brackets 208 to one arm 210 of a bell crank lever 212, the other arm 214 of which engages the under side of the starting handle 26. The rod is normally urged to the left, Fig. 1, by a spring 216 pressing against a collar 218 on the rod to force the collar to engage the innermost of the two brackets 200, thus to maintain the slide 190 in a position in which it can engage the pawl 168 upon rotation of the arm 20 about its pivots in a clockwise direction, Fig. 1. The spring 216 normally operates to force the arm 214 in a direction to maintain the starting handle 26 at the upper portion of the spindle 76 in contact with the under side of the plate 88.

The mechanism for effecting a power operation of the hammer comprises two stiff springs 220, the lower ends of which are secured to spring perches 222 carried by the block 46, the upper ends of the springs being connected to a pivot 224 carried by a block 226 arranged to engage the upper surface of the rod 126. The block is in the form of a casting having two downwardly extending spaced plates 228, between which are mounted rollers 230 adapted slidably to engage the rod 126. The block 226 is pivotally mounted upon two vertically extending rods 232 slidable vertically in the blocks 50 and 52, which serve

to guide the slide in a vertical movement while at the same time permitting the slide to move about its pivot 224, so that the rollers are maintained in engagement with the rod 126. When the valve 177 is operated to effect release of air under pressure from the cylinder 152, the springs 220 are immediately effective to force the slide 226 rapidly in a downward direction effecting rotation of the hammer 20 about its pivots, causing it to deliver a blow to the upper end of the die holder thus to drive the die through the sheet material on the cutting block.

In order to render the hammer inoperative when, for example, it is desired to make adjustments in the machine, there is provided a safety latch comprising a detent 234 pivotally mounted upon the block 50 and arranged to be moved about a horizontal axis by a handle 236. The detent can be moved into a position in the path of the downward movement of the rod 126, and serves to prevent movement of the hammer into engagement with the die holder.

In the operation of the machine sheet material 14, to be cut into blanks, is positioned upon the cutting block 12. The operator grasps the starting handle 26, raising it to lift the die 16 above the work, moves the handle over the block to locate the die in operative position for cutting a blank, and then depresses the handle to initiate operation of the hammer 24 in forcing the die through the material. During movement of the handle in positioning the die on the work, by reason of the construction of the mountings for the die holder 18 and the hammer 24, the hammer is maintained in fixed alignment relatively to the die holder, and is held in elevated position above the holder by fluid under pressure supplied to the upper side of the piston 150 in the cylinder 152. Upon depression of the handle 26 the valve 177 is operated to shut off the fluid supply and to relieve the pressure in the cylinder through the exhaust port 170, whereupon the springs 220 force the hammer down upon the die holder. When the handle is released, the spring 216 operates the valve 177 to shut off the exhaust port and to open the fluid supply line to the cylinder, thus to effect downward movement of the piston resulting in the raising of the hammer into its original position above the holder.

Having described my invention, what I claim as new and desire to secure by Letters Patent of the United States is:

1. A dieing-out machine comprising a frame, 55 a cutting block mounted in the frame, a bracket carried by the frame and mounted for movement about a vertical axis, an arm carried by the bracket and pivotally mounted thereon for movement about a horizontal axis, a die carried at an end of the arm for movement across the cutting block, a hammer pivotally mounted upon the bracket for movement toward and away from the die, means normally operative to maintain the hammer in raised position above the die, and 60 means for causing the hammer to deliver a blow to the die.

2. A dieing-out machine comprising a frame, 70 a cutting block carried by the frame, a die movable over the cutting block, means for supporting the die comprising an arm, means mounting the arm for movement about horizontal and vertical axes and for linear movement transversely of the cutting block, a hammer, means for mounting the hammer for movement across the surface of the cutting block in predetermined

relation to the die, and means for causing the hammer to deliver a blow to the die.

3. A dieing-out machine comprising a frame, a cutting block carried by the frame, a carriage mounted for movement laterally of the cutting block, a bracket mounted upon the carriage for movement about a vertical axis, an arm pivotally mounted upon the bracket for movement about a horizontal axis, a die supported at one end of the arm for movement over the cutting block, a hammer pivotally mounted upon the bracket for movement heightwise of the cutting block, and means for causing the hammer to deliver a blow to the die.

4. A dieing-out machine comprising a frame, a cutting block, a carriage mounted at one side of the cutting block for movement toward and away from the block, a bracket mounted upon the carriage for movement about a vertical axis, an arm pivotally mounted upon the bracket for movement about a horizontal axis, a die carried at one end of the arm for movement over the cutting block, a hammer pivotally mounted upon the bracket for movement about a horizontal axis, a fluid chamber mounted on the carriage, a piston mounted in the chamber, a link connecting the piston with the inner end of the hammer, means for supplying fluid under pressure to the chamber for normally maintaining the hammer in inoperative position above the die, manually operable means for releasing the fluid from the chamber, and spring-operated means for causing the hammer to deliver a blow to the die.

5. A dieing-out machine comprising a frame, a cutting block carried by the frame, a die holder, a die carried by the holder, means for mounting the die holder for movements heightwise and transversely of the block in positioning a die upon work to be operated upon, a hammer, means for mounting the hammer for correlated movements with the die, means for normally maintaining the hammer in inoperative position above the die, manually operable means for releasing the last-mentioned means to render the hammer operative, and means for causing the hammer to deliver a blow to the die.

6. In a machine of the character described, a frame, a cutting block carried by the frame, a carriage movable transversely of the cutting block, an arm pivotally mounted upon the carriage for movement about horizontal and vertical axes, a die carried at the outer end of the arm for movement over the cutting block, a hammer pivotally mounted upon the carriage for movement with the arm about a vertical axis, means for mounting the hammer for movement about a horizontal axis toward and away from the die, fluid pressure-operated means normally effective to maintain the hammer in raised position above the die, spring-operated means for causing the hammer to deliver a blow to the die, and manually operated means associated with the die for initiating an operation of the spring-operated means.

7. A dieing-out machine comprising a frame, a cutting block mounted upon the frame, a carriage mounted upon the frame for movement laterally of the cutting block, an arm pivotally mounted upon the carriage for movement over the cutting block, a die carried at an end of the arm and movable with the arm over the cutting block and heightwise thereof, a hammer, means for mounting the hammer upon the carriage for movement angularly over the cutting block in predetermined relation to the die, and means for

moving the hammer heightwise of the cutting block in delivering a blow to the die to force it through material positioned upon the block.

8. A dieing out machine comprising a frame, a cutting block carried by the frame, an arm pivotally mounted for movement angularly over the cutting block and for movement heightwise thereof, a die, means for yieldably supporting the die upon an end of the arm, a hammer, means for mounting the hammer for movement angularly over the cutting block with the arm, and means for causing the hammer to deliver a blow to the die.

9. In a dieing out machine, a cutting block, an arm pivotally mounted upon the frame of the machine at one side of the cutting block, a die holder comprising a head and an upstanding spindle, means for securing the spindle to the end of the arm, a hammer, means for mounting the hammer for movement with the arm angularly over the block, a die mounted in the head, and means for causing the hammer to deliver a blow to the end of the spindle to force the die through material positioned upon the block.

10. A dieing out machine comprising a frame, a cutting block mounted upon the frame, an arm pivotally mounted upon the frame for movements angularly over and heightwise of the cutting block, a die carried by an end of the arm, a second arm mounted upon the frame for movement with the first-mentioned arm angularly over the block, a hammer carried by the second-mentioned arm, means normally operative for holding the hammer in raised position above the die, means for causing the hammer to deliver a blow to the die, and a guard carried at the end of the first-mentioned arm and surrounding the area of contact between the hammer and the die.

11. A dieing out machine comprising a frame, a cutting block carried by the frame, a die holder having a head and an upstanding spindle, a die carried by the head, an arm pivotally mounted upon the frame of the machine, means for securing the die holder to an end of the arm, a hammer mounted for movement toward and away from the spindle for delivering blows to the spindle to force the die through work positioned upon the block, power-operated means for effecting movements of the hammer, and a manually operable starting handle mounted on the spindle for initiating actuation of the power-operated means.

12. A dieing out machine comprising a frame, a cutting block mounted upon the frame, a carriage slidably mounted on the frame for movement toward and away from the cutting block, a bracket pivotally mounted upon the carriage, an arm pivotally mounted upon the bracket for angular movement about a horizontal axis, a die carried at the outer end of the arm, a second arm pivotally mounted upon the bracket for movement about a horizontal axis, a hammer carried by the second-mentioned arm and movable with the arm in the plane of the first-mentioned arm, spring-operated means for forcing the hammer toward the die, fluid pressure-operated means normally effective to maintain the hammer in raised position over the die, and manually operable starting means for rendering the fluid pressure means inoperative thereby causing the hammer to deliver a blow to the die.

13. A dieing out machine comprising a frame, a cutting block mounted upon the frame, a cutting die, means for supporting the die comprising an arm pivotally mounted upon the frame for movement angularly over and heightwise of

the block, a hammer mounted upon the frame for movement angularly over the block with the die, means normally operative to maintain the hammer in spaced relation above the die, manually operable means associated with the die for releasing the last-mentioned means, and means for effecting an operation of the hammer upon the die to force the same through material positioned upon the block.

14. A dieing out machine comprising a frame, a cutting block mounted upon the frame, a carriage mounted upon the frame at one side of the cutting block, an arm pivotally mounted upon the carriage for movement about horizontal and vertical axes, a die carried by an end of the arm in juxtaposition to the cutting block, a counterweight upon the other end of the arm, a hammer, means mounting the hammer for movement angularly over the block in predetermined relation to the die, fluid pressure means normally operative to maintain the hammer in inoperative position above the die, means for causing the hammer to deliver a blow to the die upon release of the fluid pressure means, and manually operable means associated with the die for releasing the fluid pressure means.

15. A dieing out machine comprising a frame, a cutting block mounted in the frame, an arm pivotally mounted upon the frame for movement

angularly across the block and heightwise thereof, a cutting die carried at one end of the arm, means for securing the die to the arm comprising a die holder having an upstanding spindle, a bracket mounted upon the end of the arm and having an opening for receiving the upper end of the spindle, and spring pressed means carried by the bracket for engaging the spindle to lock it in fixed position heightwise of the bracket.

16. A dieing out machine comprising a frame, a cutting block mounted upon the frame, a bracket mounted upon the frame at one side of the block for movement about a vertical axis, two arms pivotally mounted upon the bracket for movement in the same vertical plane about horizontal axes, a die carried by one of the arms and a hammer by the other of the arms, a pressure chamber carried by the bracket, a piston mounted in the pressure chamber, means connecting the piston with an end of the arm associated with the hammer, means for supplying fluid under pressure to the pressure chamber thereby to cause the piston to move the hammer away from the die, a starting handle associated with the die, means operable by the starting handle to release fluid pressure in the chamber thereby to release the hammer for an operation upon the die.

GEORGE F. RYAN.
